UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 13,897, dated November 7, 1882.

Application filed August 11, 1882. Term of patent 3½ years.

To all whom it may concern:

Be it known that I, HENRY HUNT, of Greenville, in the State of New Jersey, have invented a new and original Design for Carpets, of which the following is a specification.

5 This invention relates to a new and original design for carpets and similar fabrics; and it consists in the novel grouping and configuration of figures hereinafter more fully described.

10 The accompanying photograph illustrates a face view of a carpet having my new design.

The design consists of a number of irregularly-shaped panels in places overlapping one another, each ornamented centrally by a flower-group resting either on a plain field or on a field filled with small regular figured work, and bounded by borders, usually broad and right-lined.

15 The panel A has a flower-group resting on a plain field. On the left, and also partly above, is a broad border ornamented by circular figures, and terminating below in a large rosette. A similar border, but differently ornamented, bounds the panel below and partly on the right, terminating in a Greek key. At the right upper corner of the panel is a large rosette.

20 The panel B has a flower-group resting on a mural field above and on the left. It is hexagonal in shape, having a wide border ornamented with small square and crossed figures, and terminating to the right in a large rosette. Along part of the lower side is a broad border

ornamented with small running figures. The part of the panel shown on the left lower corner of the photograph is rectangular in shape, and is bounded below and on the right by narrow borders differently ornamented.

35 The large panel C has a flower-group resting on a figured wicker-work field. On the left below it has a broad border with small ornamental work, terminating above in a flower-like rosette and leaf-cluster.

40 The panel D has a flower-cluster resting on a plain field. Above it has a broad border with small ornamental work, and for a short distance below and on the left is a narrow border bearing at the corner a large square figure with a rosette at its center.

45 I claim—

50 1. The design for carpets, consisting of the panel A, substantially as shown.

2. The design for carpets, consisting of the panel B, substantially as shown.

3. The design for carpets, consisting of the panel C, substantially as shown.

4. The design for carpets, consisting of the panel D, substantially as shown.

5. The design for carpets, consisting of the panels A, B, C, and D, substantially as shown and described.

HENRY HUNT.
